UNITED STATES PATENT OFFICE.

WILLIAM HOCHHAUSEN, OF BROOKLYN, NEW YORK.

DYNAMO-ELECTRIC MACHINE.

SPECIFICATION forming part of Letters Patent No. 437,360, dated September 30, 1890.

Application filed February 17, 1890. Serial No. 340,716. (No model.)

To all whom it may concern:

Be it known that I, WILLIAM HOCHHAUSEN, a citizen of the United States, and a resident of Brooklyn, in the county of Kings and State of New York, have invented a certain new and useful Dynamo-Electric Machine, of which the following is a specification.

My invention relates to various features of construction of dynamo-electric machines or motors, and in some of its particulars relates especially to those provided with regulating mechanism.

The object of my invention, among other things, is to provide for the ready removal of the armature without dismantling the field-magnets, to insure the insulation of the armature from the ground, to prevent overheating of the field-magnet coils, to provide means whereby the armature may be readily centered in the magnetic field in those cases where it is subjected to attractive or repulsive influences on its side tending to give an end-thrust to the armature-shaft, to so construct and arrange the regulating mechanism that the same shall be compact and protected from injury, and to improve the various details of construction and arrangement of parts in sundry other particulars, which will be described hereinafter in connection with the accompanying drawings.

My invention consists in the improved constructions and combinations of devices hereinafter described, and more particularly specified in the claims.

In the accompanying drawings, Figure 1 is an end elevation of a dynamo electric machine embodying my invention. Fig. 2 is a side elevation of the field-magnet frame without its coils and the armature-shaft and bearings therefor. Fig. 3 is a plan of the top of the field-magnet core and pole-piece. Fig. 4 is a detail view, in side elevation, of a portion of the regulating mechanism. Fig. 5 shows in detail from the rear side the switching devices which control the number of field-magnet coils in action. Fig. 6 is a plan of the two journal-boxes with the guide and armature-shaft removed, and shows the connecting oil-trough between the same. Fig. 7 is a side elevation of a part of the regulating mechanism. Fig. 8 shows a detail of a modification in the manner of securing the two

parts of the field-magnet pole together. Fig. 9 is a plan of such modified detail. Fig. 10 is an end elevation of the portion of the field-magnet frame or yoke-piece and the journal-box for the armature-shaft. Fig. 11 is a side elevation of the journal-box and attachments shown in Fig. 10, the yoke-piece or portion of field-magnet frame in which the journal-box rests being shown in section. Fig. 12 is a diagram of the connections of the machine and its regulating mechanism, and shows in plan a part of the controlling mechanism for the regulator.

A A are the two legs of a field-magnet of general **U** form, and A² the connecting yoke-piece between such legs. The legs A A are the core-pieces upon which field-magnet coils are wound, as well understood in the art, to develop magnetism in the pole-pieces B B, between which the armature mounted on the armature-shaft D rotates. The field-magnet coils O O are wound in two or more superimposed sections, which are held separated from one another by blocks or strips O², preferably of wood, thus leaving free air-spaces between the coils, through which ventilating air-currents may be forced or may circulate for the purpose of preventing overheating of such coils. The flanges or spool-heads which bound the coils at their ends are provided with openings O³, communicating with the ventilating-spaces, so as to allow ready circulation of the air from end to end of the field-magnet. To assist in the ventilation, air-spaces might be left at intervals in each section of the winding, which would permit air to circulate down through the coils, as well as from end to end. Such a ventilating-space is indicated in Fig. 2 at O⁷.

I do not limit myself to the manner of holding the superimposed sections apart to permit the circulation of air, but prefer to employ separating-strips O², running from end to end of the coils.

The pole-pieces B B are grooved at their inner sides, as shown, so that the sides of the armature will be exposed directly to magnetic action.

To permit the armature and attached shaft to be slipped readily out of the field-magnet frame, I make the outer portion b of the pole-piece separate from the other portion and

clamp the two parts together by bolts B^3 or other devices, which join the outer portion b to the inner portion in a plane parallel to the plane of revolution of the armature-shaft. 5 The line of division might be a central line, as shown, or might be removed to one side or the other, as is evident, provided, however, that the line be such that the outer portion of the pole-piece, which extends down over 10 the side of the armature, may be moved away from the inner portion or body of the pole-piece and field-magnet.

At B^2 , I have shown suitable hinges, whereby the portion b of the pole-pieces is supported, so that on taking out the bolts B^3 the outer portion b may be swung back, so as not to be in the way of the armature when the same is moved endwise with the armature-shaft. It is convenient to form both pole-pieces in the 20 manner described, so that the outer portions of both the top and the bottom pole-pieces may be turned or swung back when the armature is to be removed.

At H is indicated a connecting-piece between the pole-pieces, which piece is in effect a strut holding the parts of the field-magnet frame rigidly in position at the pole end. The strut H forms a support also for the armature-shaft at one end. It is preferably bolted to 30 the pole-pieces, as indicated.

In order to obviate the necessity of withdrawing the bolts or fastening devices B^3 entirely when the armature is to be removed, the fastening devices may be constructed as indicated in Figs. 8 and 9, where the bolt is hinged at B^7 to the body of the pole-piece, and the stud or projection B^8 on the movable portion b of the pole-pieces is open at its top, so that after the tightening-nut is loosened 40 the bolt may be swung back out of the way.

I do not limit myself to any particular location of the hinge for the pivoted or hinged portion of the pole-piece, nor to swinging said portion back in any particular plane, although I have shown it in the drawings as 45 swinging in a vertical plane, or plane coinciding with the plane of the field-magnet legs A . A ; nor do I limit myself to any particular means for fastening the outer portion b to the inner portion.

C are iron arms, which are bolted or fastened to the pole-pieces of the machine and curve toward one another in a plane parallel to the armature-shaft. These arms C terminate in pole-pieces C^3 C^2 , between which rotates the armature C^3 of the electric motor, which operates the regulating mechanism of the machine. The armature C^4 of such motor, as indicated in Fig. 7, has a bearing at 60 one end in a bracket C^5 , fastened to one of the arms C , and at its other is mounted in a bracket or bearing C^6 , that extends from a plate secured to and joining the two pole-pieces C^2 at the opposite side of the arms C .

65 The armature of the motor may be wound in any desired way, but is conveniently a Gramme-wound armature.

The commutator-brushes are indicated at a a^2 . These brushes are suitably mounted on an insulating-block b , fastened or secured to the arm C in any desired way, and may be of any desired construction and provided with suitable devices for connecting the wires which carry the current to the brushes and armature. 75

The commutator of the dynamo-machine (indicated at D^2) is mounted upon the armature-shaft D of the machine in any usual or proper way and is of any desired construction.

The swinging yoke or arm which supports the commutator-brushes is indicated at D^3 , and is fastened to a spindle or rock-shaft D^4 , mounted in suitable bearings in the upper arm C . Connected to the swinging yoke D^3 is a segmental rack E^4 , supported from such yoke by arms E^7 E^8 . Movement is communicated to the rack and yoke from the motor-armature C^3 by means of gear consisting of pinion E on the armature-shaft C^4 and gear-wheel E^2 , carried by a counter-shaft, which is provided with a pinion E^3 , gearing with the rack E^4 , and is mounted in a suitable bracket or support extending from the lower arm C or from the connecting-plate which joins the two arms at their rear side. 90

C^4 C^4 are connecting brass plates, which join the pole pieces C^2 C^2 and hold them rigidly in position. The movement communicated to the brushes of the commutator by the mechanism described is for the purpose of 100 keeping such brushes at the neutral or non-sparking point when changes in the strength of the field-magnetism are produced by the operation of the motor for the purpose of regulating the current or potential of the machine. 105

The variations of the strength of the field-magnetism are produced by switching the field-magnet coils into and out of circuit or by shunting them from circuit through the 110 operation of switching appliances, the movable contacts of which are indicated at F^4 F^4 , carried by a vertically-sliding bar F^5 .

G^2 G^2 are boxes in which are fastened the two series of contact-points G G , which contacts are insulated from one another by mica or other suitable material, and are joined at the end opposite their contact end in any suitable way to the sections of field-magnet coils. The boxes G^2 are mounted, as shown, 115 on the field-magnet frame between the two sides or legs of the field-magnet and in position where they cannot be readily disturbed. I prefer to fasten them, as indicated, to the strut H by suitable screws that pass through 120 ears or projections from the switch or contact boxes. The contact-springs F^4 are in electrical connection with one another, being mounted, without insulation, upon a common conducting-block; but the supporting-bar F^5 , by which 125 they are carried, is guided up and down in insulating-bearings F^7 , projecting from or secured to the boxes G^2 . The bar F^5 is controlled 130 by the electric motor-armature C^3 through the

medium of an adjustable link E⁵, attached at one end to the segmental rack E⁴, or other part moving with it, and at the other to a crank E⁶, fastened to a rock-shaft F. The rock-shaft F is 5 mounted in a suitable frame or bearings fastened to the lower pole-piece B and extends rearwardly from the outer side of the pole-piece to the inner side in a direction parallel with the armature-shaft of the machine, and is provided at its end opposite from E⁶ with a crank-arm F², which connects to a link F³, pivoted to the bar F⁵, or part carried by it. The link or pitman E⁵ is adjustable, as shown, at one of its ends—as, for instance, in that connected 10 to the crank-arm E⁶—in a slot in such crank-arm to and from the pivot of the crank-arm, so that the throw of the switching devices which regulate the field-magnet strength under the action of the motor may be adjusted. 15 The length of the link or pitman E⁵ is also adjustable, so that when the end of the link is moved in toward the pivot of the arm E⁶ the link E⁵ may be properly shortened, so that the normal relation in the position of the yoke 20 D³ and the switching devices governing the field-magnet strength may be maintained with the change of adjustment, and so that, if necessary under any conditions, the relation may be changed in case it should be found that, 25 30 with the switching devices in normal position, the yoke D³ is in position to hold the commutator-brushes forward or back of the neutral or non-sparking point. By thus organizing and operating the devices together the motor, 35 when it rotates to operate the switch and cut down the field-magnetism may also act to shift the brushes of the commutator of the dynamo to the proper point to prevent sparking with the change in the field-magnet 40 strength.

The action of the motor is governed by a controller-magnet P, as shown in Fig. 12, such magnet being in the main circuit when the regulation is one for constant current. The 45 controller-magnet is mounted upon a suitable slate or other base S, and is provided with a circuit closing and breaking armature-lever P², which is a contact operating on a double-contact rocking lever P³ after the manner described in my prior patents, Nos. 294,038 and 294,039, dated February 26, 1884.

R' R² R³ indicate three several artificial resistances placed in separate branches of the circuit, as will be presently described. Two 55 of these resistances R' R² are connected to the circuits 2 3, and the terminals of the motor to the two contacts d d² of the rocking contact-lever P³, while the third resistance R³ is in a safety branch designed to afford a path for the 60 current in case the circuit should be broken through the contacts of the controller or in the motor.

The sections of the field-magnet coil are connected in regular order to the contacts G, 65 the beginning of the series of sections on one of the legs of the magnet being connected to the upper contact G of the upper box, while

the last section connects to the lower contact of the same box, the intermediate sections being connected in regular order. From the 70 last section a connection is taken to the first section of the other field-magnet leg, such first section being connected to the lower contact of the lower box, while the upper contact of the lower box connects to the last section of 75 the second field-magnet leg and to the continuation of the circuit.

In the position of the contact-springs G⁸ G⁸ shown in Fig. 13 it is obvious that they will form a shunt-circuit around the field-magnet 80 coils, and no current or practically no current will flow in such coils. In the other extreme position of the contact-springs the current will flow through all the sections of both legs of the field-magnet, while on a return move- 85 ment of the contact-springs toward the position shown the coil-section of each leg will be gradually shunted out of circuit in pairs, thus decreasing the strength of the field-magnetism. Simultaneously with such adjustment 90 to decrease the strength of the field-magnetism and the electro-motive force of the machine the yoke D³ will be moved into a position to shift the brushes of the commutator D² forward. 95

The connections from the controller-magnet P and associated devices and from the external circuit to the circuits of the dynamo and regulating-motor are made as follows: through metal bolts N' N² N³ N⁴ N⁵, mounted 100 on the insulating-blocks on the top of the upper field-magnet pole P, and at the point of union of the outer movable portion b with the body of the pole-piece. The bolts themselves are mounted on one part, and contact- 105 sockets for the same are mounted on the other part, so that by moving the bolts or slides back the connections will be broken and the outer portion b of the upper pole-piece may be swung back without interference from 110 such connecting devices. From the connecting-slides N' N⁴ flexible connections run to the two commutator-brushes bearing on the commutator D³, while from the slides or connecting devices N² N³ similar flexible connections run down over the arm C or otherwise 115 to the two brushes a a² of the motor. The field-magnet circuit has its two poles connected, respectively, as shown in Fig. 13, to the connecting slides or blocks N⁴ N⁵. A 120 switch N⁶ may be thrown in to connect such blocks for the purpose of destroying the field-magnetism when the main switch of the circuit is to be opened, thus preventing destructive arcing. 125

Connections are made to the points 1 2 3 4 on the controller-box as indicated, and the circuits thus formed will be as follows: From block N⁵, connected to one terminal of the field-magnet coils, the circuit passes to 4, 130 through the coils of controller-magnet P, to the conducting-support of armature P², thence to the armature and through both contacts d d² when the current is normal, thence from

such contacts through resistance R' R^2 to point 1 and by way of the external circuit to the connecting-block N' , thence through the armature of the machine to the connecting-block N^4 , and by way of the field-magnet coils and regulating-switch back to the connecting-block N^5 . The armature of the motor has its terminals connected, as shown, by contact-blocks N^2 N^3 to points 2 3 of the controller device, and thence to the points of connection of resistance R' R^2 and to the contacts d d^2 of the controller. Under this condition of the circuits and apparatus no current flows through the motor, its terminals being connected to points of equal potential of the circuit. Should the current in the main circuit passing through the coils P decrease so as to allow the armature-lever P^2 to be thrown back and break at one of the contacts, as d^2 , or to relieve the contact at such point, the current will then pass by contact d to the point of connection of resistance R' , and while a part of the current will circulate directly through such resistance to the line another part will pass by way of point 3 through the armature of the motor back to point 2 and through the resistance R^2 to the continuation of the circuit, thus causing the motor to revolve in a direction to increase the field-magnetism. Should the current increase beyond normal, the circuit at contact d of the controller will be broken, and the current will pass by way of d^2 in two paths, one of which includes resistance R^2 , while the other is by way of point 2 through the armature of the motor to the point 3 by resistance R' to the line, the current in this instance circulating through the motor in an opposite direction to that just supposed, so as to reverse the movement of the regulating motor and mechanism and cut down the strength of the current on the circuit.

The resistance R^3 , as shown, is in a connection from the frame on which the armature P^2 is mounted to the point 4, where the line is connected, and current may flow, therefore, from connecting device N^5 , part upon 1, magnet P , and resistance R^3 , directly to the outside line, avoiding the contacts of the controller and the electric motor. This resistance forms a safety branch or circuit whereby a path may be afforded for the current of the machine to the external circuit in cases where, through carelessness in adjustment or through any other cause, the circuit may be completely interrupted at both contacts of the controller. The switch P^4 , applied as shown, serves to form a shunt around all of the regulating devices and resistances excepting the coils of the regulator-magnet P . This switch will be found useful when it is desired to restore or repair any parts of the regulating appliances.

The armature of the machine may be of any desired form or construction and mounted upon the armature-shaft D in any proper or desired way.

To insure the insulation of the armature and to permit it to be centered in the magnetic field formed by the grooved pole-piece, I construct and mount the armature-shaft as follows: I I^2 indicate the lower halves of journal-boxes at opposite ends of the machine, and I^6 I^6 the journal-box caps. These two journal-boxes form the bearings for the armature-shaft and are supported, respectively, in the yoke-piece A^2 and on the strut or connecting-piece H between the field-magnet poles. The lower halves of the journal-boxes are connected, as shown, by a bar I^8 , which may be cast in one piece with the said journal-boxes or may be attached to them, as desired. It is preferable, however, to cast the whole in one piece. By this construction the two journal-boxes and the shaft mounted in them may be moved longitudinally together.

At I^4 are indicated oil wells or reservoirs, from which the oil is fed up by wicks, as usual, to the brasses and shaft. These oil-wells are connected by the longitudinal oil-way I^5 , formed, preferably, in the part I^3 , so that if lubrication be applied only to one box the oil will pass to and lubricate the other also.

At the rear end of the machine, or the end opposite the armature, the connected journal-boxes form a flange K , extending down over the edge of the opening in the yoke-piece A^2 . Through this flange pass pull and push screws L^2 L , by which the journal-boxes and supported shaft with the armature may be positively moved in either direction and set in position. The push-screws L pass through insulating-bushings in the flange K and are tapped in the yoke-piece A^2 or other support. The pull-screws L^2 are tapped in the flange K and bear against the yoke-piece A^2 , but are insulated therefrom preferably by insulation as indicated at M . Insulation of any suitable character is also interposed at M^2 beneath the under side of the connected journal-boxes and between the same and the yoke-piece, and also between the flange K and the outer side of the yoke-piece, thus thoroughly insulating the armature and preventing connections to ground. To hold the journal-boxes firmly in their supports, I employ set-screws L^3 , which pass through the projections L^4 from the yoke-piece and bear downwardly upon the end of the connected yoke-pieces or the flange K . Insulation M^3 is applied at the point of bearing or at other points to prevent connection between the armature-shaft and the frame of the machine.

By means of screws L L^2 it is obvious that the bearings may be moved together into any desired position with the armature-shaft and armature supported in them.

What I claim as my invention is—

1. In a dynamo-electric machine or motor, a field-magnet pole-piece the outer portion of which is hinged to permit it to be opened back when the armature is to be removed.
2. In a dynamo-electric machine or motor, a field-magnet having a projecting or salient

grooved pole-piece the outer portion of which is clamped to the inner portion supported by the magnet and is joined to such inner portion in a plane parallel to the plane of revolution of the armature-shaft.

5 3. In a dynamo-electric machine or motor, a projecting or salient grooved pole-piece bisected on a line parallel to the plane of revolution of the armature to permit the part 10 coming down over the outer side of the armature to be moved, as and for the purpose described.

4. In a dynamo-electric machine or motor, a grooved pole-piece, a section b of which is 15 separated from the main portion, in combination with a hinged support B^2 and suitable clamping-bolts B^3 .

5. In a dynamo-electric machine or motor, field-magnet coils wound in two or more superimposed sections separated from one another by ventilating-spaces, the outer section being subdivided by spaces O^7 , communicating with the spaces separating the superimposed sections.

25 6. In a dynamo-electric machine or motor, the combination, with the field-magnet coils wound in two or more sections, of separating-blocks O^2 , interposed between such sections and separated from one another by air-spaces, 30 the outer section being subdivided into sections separated by spaces O^7 , as and for the purpose described.

7. The combination, with the field-magnet coils wound in superimposed sections separated from one another by ventilating-spaces, 35 of magnet spool-heads having perforations or openings opposite such spaces and spaces O^7 between parts of the outer section, as and for the purpose described.

40 8. The combination of the regulating electric motor, an adjustable commutator the adjustable member of which is geared to the motor, a field-magnet switch-box mounted between the field-magnets of the generator, and 45 the counter-shaft between the movable switch-contacts and the regulating electric motor.

9. The combination, with the regulating motor and the adjustable commutator, of the switch mechanism controlling the strength of 50 the field-magnet, the generator, and intermediate connecting devices between such switch and motor, having adjusting mechanism whereby the throw of the switch as compared with the throw of the adjustable commutator may be regulated.

55 10. The combination, substantially as described, of the regulating electric motor, the commutator-yoke carrying a segment geared to such motor, the adjustable switch governing the connections of the field-magnet coils for determining the strength of such field-magnet, the rock-shaft having crank and connections to the movable part of the switch, and a link or pitman E^5 , for connecting such 65 rock-shaft with the motor.

11. The combination, with the adjustable commutator and the actuating electric motor,

of the adjustable switching devices governing the circuits of the field-magnet and a connecting rock-shaft and pitman between 70 the motor and switch, such pitman having means for adjusting its length and its point of attachment to the crank of the rock-shaft for varying the throw.

12. The combination, substantially as described, with the adjustable commutator, of an electric motor geared thereto and having its armature placed in the field between the polar ends of the two arms extending from the field-magnet poles in a plane parallel with 80 the armature-shaft, an electric switch controlling the connections of the field-magnet coils for varying the strength of such field-magnet and mounted between the legs of the field-magnet, a rock-shaft parallel with the 85 armature and extending from the outside of the field-magnet poles toward the inner side thereof, and connections from such rock-shaft to the electric motor and to the movable contacts of the switch, as and for the purpose 90 described.

13. The combination, substantially as described, of the adjustable commutator, the actuating electric motor having its armature mounted between the polar extensions from 95 the field-magnet poles of the machine, a controlling-switch having connections to the field-magnet coils, an adjustable switch-contact for determining the strength of the field-magnet, a rock-shaft mounted in bearings secured to 100 the pole-piece of the machine, and links or pitmen connecting such rock-shaft to the electric motor and the movable contacts of the switch.

14. The combination, with the sectional 105 field-magnet pole, of connecting boxes or slides the two members of which are mounted, respectively, on the two sections of the field-magnet pole and form a portion of the connections between the external circuit and the 110 machine, as and for the purpose described.

15. The combination, with the connecting boxes or slides mounted on the field-magnet poles, of a shunting switch N^6 between the contacts or slides connected, respectively, to 115 the terminals of the field-magnets of the machine.

16. The combination, with a dynamo-electric machine, of regulating appliances therefor, a controller-magnet and controller-contacts governing an electric motor which actuates the regulating appliances, said contacts and motor being in series with the translating devices or main circuit, and a permanent safety-resistance R^2 , forming a safety-shunt 120 125 for the main-line circuit around such contact and motor.

17. The combination, with the controller-magnet, controller-contacts, and the resistances $R' R^2$, placed in the circuits from the 130 connections to the motor-armature, of the switch P^4 , placed in a shunt around such contacts and resistances.

18. The combination, with the controller-

contacts and the motor-armature connected thereto, both placed in the main-line circuit, of a permanent branch resistance R^2 around said contacts and motor and a shunting-
5 switch P^4 for shunting said resistance out of the main line.

19. In a dynamo-electric machine or motor, the combination, with the armature-shaft, of journal-boxes supported on the field-magnet
10 frame and insulation interposed between such boxes and frame.

20. The combination, with a dynamo machine or motor, of an armature-shaft and connected journal-boxes longitudinally adjustable in supports formed on the field-magnet,
15 as and for the purpose described.

21. In a dynamo-electric machine or motor, the combination, with the two journal-boxes mounted in the field-magnet, of the connecting-piece I^3 , parallel with the field-magnet core.
20

22. The combination, with the armature-shaft, of journal-boxes, the lower halves of which are cast in one piece with a connecting-piece I^3 and are properly mounted in the yoke-piece of the field-magnet, and a strut connecting the pole ends thereof.
25

23. The combination, with the armature-shaft, of the two connected journal-boxes mounted in the field-of-force magnet and having oil-wells connected by an oilway.
30

24. The combination, with the armature-shaft and the connected journal-boxes therefor, supported in the yoke-piece for the field-magnet and in a strut connecting the pole ends of said magnet, of the adjusting pull and push screws for adjusting and setting the same in any desired longitudinal position.
35

25. The combination, with the armature-shaft and connected journal-boxes resting at 40 one end in the yoke-piece of the field-magnet frame, of a flange at the rear end of the machine and adjusting-screws tapped in and bearing against the connecting part A^2 of the field-magnet frame.
45

26. The combination, with the armature-shaft and connected journal-bearings therefor, of an adjusting-screw L^2 , bearing against but insulated from the field-magnet frame.

27. The combination, with the connected 50 journal-bearings and armature-shaft mounted therein, of an adjusting-screw tapped in the frame of the machine, but insulated from the bearings.

28. The combination, with the connected 55 journal-bearings and armature-shaft, of insulating material for insulating the bearing from the field-magnet frame.

29. The combination, with the connected journal-bearings carrying the armature-shaft, 60 of adjusting mechanism for adjusting and setting the bearings and shaft in different longitudinal positions and insulating material, applied as described, to prevent electrical connection between the journal-bearings and 65 the parts of the field-magnet frame upon which the adjusting mechanism bears.

Signed at New York, in the county of New York and State of New York, this 7th day of February, A. D. 1890.

WILLIAM HOCHHAUSEN.
